UNITED STATES PATENT OFFICE

2,167,091

BURIAL VAULT

Robert Simpson, Casper, Wyo.

Application February 17, 1938, Serial No. 191,102

15 Claims.

(Cl. 72—7)

The present invention relates to burial vault constructions. More particularly, the invention is directed to modifications of or improvements on vaults of the type shown and described in my copending application Serial No. 137,337, filed April 16, 1937, now Patent No. 2,111,462.

It is an object of the invention to improve the construction of vaults of the foregoing type, particularly as regards the concrete, stone, or masonry parts thereof. It is a further object of the invention to provide means for preventing the moisture which forms on the interior surface of the vault from collecting therein. To this end, novel means are provided to effect drainage of such moisture, without permitting passage of air or gases to and from the inside and the outside of the vault.

It is a further object of the invention to provide a vault which is characterized by great strength and ruggedness, so that the vault will not deteriorate in any manner throughout the lapse of time.

In the accompanying drawing, two forms of the invention are disclosed. It must be understood that the invention is not limited to the specific details of construction shown and described below, but includes all modifications falling within the scope of the appended claims, and their equivalents.

30 In the drawing:

Figure 1 is a vertical longitudinal sectional view of one form of vault.

Figure 2 is a sectional view on line 2—2 of Figure 1.

35 Figure 3 is a vertical longitudinal sectional view of a second form of vault, and

Figure 4 is a transverse section on line 4—4 of Figure 3.

The vault preferably comprises a monolithic, 40 concrete foundation slab 10 adapted to be positioned in the bottom of the grave. A slab of this kind is desirable because it increases the bearing surface in the ground and serves to distribute the weight of the vault over a large area. As a 45 result, settling of the vault in the ground and lateral tipping of the same is prevented. The foundation slab is provided around its upper margin with a rabbeted portion comprising inclined surfaces 11 and 12.

50 These surfaces support the lower edges of the base portion 13 which, in Figure 1, comprises a top wall 14, end walls 15, 16, and side walls 17, 18. The lower edges of the side and end walls are downwardly and outwardly inclined, as indicated, and mate with the downwardly and outwardly inclined surface 11 of the foundation slab.

The top wall 14 of the base serves as a casket supporting floor and its upper surface is inclined downwardly and inwardly toward a central aper-

ture 19, which serves as a drainage hole, as hereinafter explained.

The upper surface of the base is provided with a rabbeted marginal edge, formed by downwardly and outwardly inclined surfaces 20 and a vertical surface 21. Also, a groove 22 is formed in the upper surface of the floor 14, spaced inwardly from the margins thereof.

The casket enclosing receptacle, in the form shown in Figures 1 and 2, comprises a top wall 10 10 23, depending side walls 24, 25, and similar end walls 26, 27, forming an inverted, open bottom box or hood. The lower edges of the side and end walls are preferably downwardly and outwardly inclined, as shown in the drawing, to rest 15 upon and mate with the inclined surfaces 20 around the upper margin of the base.

A cover slab 28 may be positioned upon the top wall 23. This slab and head stone 29 may be made from decorative material, such as marble, 20 limestone, or the like.

Within the casket receptacle there is positioned an inner casing 30 which is preferably similar to the inner casing shown in the copending application referred to above. In the present case, however, the inner casing 30 has its top wall 31 and its side and end walls 32 and 33 spaced from the inner faces of the adjacent walls of the casket receptacle. This spacing of the walls is advantageous, since it facilitates positioning of the heavy concrete outer casing over the inner casing after the latter has been put in place over the casket supported on the base 14.

The lower edges of the inner casing are sunk in the grooves 22 and sealed therein with an 35 appropriate waterproof, asphaltic cement. The inner casing is preferably made of sheet copper or bronze, and the meeting joints between the side, end and top walls are welded or soldered to provide an hermetic seal.

The space between the inner casing and the side walls of the casket receptacle permits water of condensation which forms on the walls to run downwardly. The joint between the walls of the casket receptacle and the base is preferably 45 a dry joint. Therefore, the moisture may drain downwardly and outwardly over the inclined surfaces 20 to be absorbed in the ground.

Attached to the central opening 19 in the floor 14 of the base is a drainage pipe 35, having 50 formed therein a double reverse bend or goose neck 36, thereby providing a trap to prevent the passage of air and gases between the casket receptacle and the hollow, downwardly opening space in the base. The lower end of the pipe 35 55 is positioned adjacent the foundation slab 10.

It will be appreciated from the above that an extremely rugged and efficient vault is provided by the construction shown in Figures 1 and 2. Means are provided for draining the moisture 60

which collects on the inner faces of the casket receptacle. The moisture which may be present inside of the inner casing will drain downwardly through the pipe 35 to the space in the hollow base. The moisture can escape through that space by flowing through the dry joint between the walls of the base and the surfaces 11, 12 of the foundation slab.

The second form of the invention differs from the foregoing primarily in that the base and the side and end walls of the casket receptacle are integral. The base 14', as in the previous case, forms the floor of the casket receptacle. Around its margins, it is provided with downwardly projecting flanges forming end walls 15', 16' and side walls 17', 18'. The joint between the lower edges of these walls and the foundation slab 10 is the same as previously described.

Around the margins of the floor 14', there are formed upwardly projecting flanges providing side walls 24', 25' and end walls 26', 27' of a casket receiving receptacle. The upper end of the casket receptacle is closed by a cover slab 23', having a rabbeted joint connection 40 with the side walls. This joint may be dry, or it may be sealed substantially in the manner shown in my aforesaid copending application.

The inner casing 30' in the second form is the same as that shown in Figure 1, with the exception that a plurality of openings or notches 41 are provided along the lower edge of the side and end walls to permit moisture which may collect on the inner faces of the walls 24'-27' to flow inwardly to the opening 19'. From this point, the moisture drains in the manner previously described.

Preferably the foundation slab, the base, and the walls of the casket receptacle, in both forms of the invention, are made of reinforced, cast concrete. The reinforcing means may be the conventional steel reinforcing elements used in similar concrete structures.

The parts are made by pouring the concrete into appropriately shaped molds, in the usual manner.

As a result of the novel features of the present invention, an improved burial vault of the "surface" type is provided. The parts are sufficiently heavy to withstand the deteriorating effects of time, and as a result, the contents of the casket will be preserved indefinitely.

As stated above, all modifications coming within the scope of the appended claims or their equivalents, are within the invention.

55 I claim:

1. A burial vault construction comprising, in combination, a foundation slab, a base comprising a top wall and side and end walls supported along the margins of said slab and providing a hollow, downwardly opening chamber above said slab, a casket receiving chamber above the top wall of the base comprised of side and end walls aligned with the corresponding walls of the base and projecting upwardly therefrom and a top wall supported thereby, and a preformed, unitary sheet metal inner casing within said chamber comprising a top wall and side and end walls hermetically sealed along their meeting joints and having an open bottom.

70 2. A burial vault construction comprising, in combination, a foundation slab, a base comprising a top wall and side and end walls supported along the margins of said slab and providing a hollow, downwardly opening chamber above said slab, a casket receiving chamber above

the base, the top wall of the base forming the bottom wall of the chamber, said chamber being further comprised of side and end walls aligned with the corresponding walls of the base and projecting upwardly therefrom and a top wall supported thereby, and a preformed, unitary sheet metal inner casing supported on the bottom wall of said chamber and comprising a top wall and side and end walls hermetically sealed along their meeting joints and having an open bottom, said open bottom being effective to permit the casing to be lowered upon the bottom wall of the chamber to enclose a casket supported thereon prior to the closing of the chamber.

3. A burial vault construction comprising, in combination, a foundation slab having a rabbeted edge around the margins of its upper surface, a base portion comprising a top wall and side and end walls supported along said rabbeted edge and providing a hollow, downwardly opening chamber, a casket receiving receptacle portion above said base portion having its bottom surface formed by the top wall of said base portion and comprising side and ends by walls projecting upwardly from and aligned with the corresponding walls of the base portion and a top wall carried thereby, and drainage means leading from the interior of said casket receiving receptacle to the hollow space in said base, whereby fluid may pass from the former to the latter and drain therefrom over said rabbeted edge of the foundation slab.

4. A burial vault construction comprising, in combination, a foundation slab, a unitary base supported thereon and comprising side, end and top walls providing a hollow, downwardly opening space, a casket receptacle above the base comprising unitary side and end walls extending upwardly from the corresponding walls of said base and a top wall carried thereby, and an inner sheet metal casing in said receptacle comprising a unitary, preformed structure including side, end and top walls hermetically sealed along their meeting edges and having an open bottom.

5. A burial vault comprising a foundation slab, a base supported along the edges thereof and comprising unitary side, end and top walls providing a hollow interior space having an open bottom closed by said slab, and a casket receptacle above said base, the bottom, casket supporting surface of said receptacle being formed by the top wall of said base, said receptacle further comprising unitary side and end walls, a top wall carried thereby, and a sheet metal inner casing supported on said bottom surface, said casing being preformed and comprising sheet metal top and side walls hermetically sealed along their meeting joints and having an open bottom, said open bottom being effective to permit the casing to be lowered upon said surface to enclose a casket supported thereon prior to the closing of the receptacle.

6. A burial vault comprising a unitary base having side, end and top walls providing a hollow, downwardly opening interior space, the lower ends of said walls being adapted to be supported substantially at the bottom of a grave, and a casket receptacle above said base, the casket supporting surface of said receptacle being formed by the top wall of said base, said receptacle further comprising unitary side and end walls, a top wall carried thereby, and a drain pipe extending through the casket supporting surface to a point adjacent the bottom of the base.

7. A burial vault comprising a unitary base having side, end and top walls providing a hollow, downwardly opening interior space, the lower ends of said walls being adapted to be supported substantially at the bottom of a grave, and a casket receptacle above said base, the casket supporting surface of said receptacle being formed by the top wall of said base, said receptacle further comprising unitary side and end walls, a top wall carried thereby, and drainage means for the casket receptacle, comprising a pipe extending through said casket supporting surface downwardly to a point adjacent the bottom of the base, said pipe having a goose-neck bend therein providing an air seal.

8. A burial vault comprising a base having unitary side, end and top walls providing a hollow downwardly opening interior space and a casket receptacle above said base, the casket supporting surface of said receptacle being formed by the top wall of said base, said receptacle further comprising unitary side and end walls, a top wall carried thereby, a preformed sheet metal inner casing supported on said bottom surface comprising sheet metal top and side walls hermetically sealed along their meeting joints and having an open bottom, said open bottom being effective to permit the casing to be lowered upon said supporting surface to enclose a casket supported thereon prior to the closing of the receptacle, and drainage means for the space enclosed within said inner casing, said means comprising a pipe extending through said supporting surface to a point at the bottom of said base.

9. A burial vault comprising a base having an upper, substantially horizontal casket supporting surface, and downwardly extending side and end walls integral therewith providing a lower, downwardly opening hollow space, means for supporting said base in a grave, and a casket enclosing receptacle supported on said base, said receptacle comprising integral, top, side and end walls and an open bottom, said bottom being closed by the top wall of said base.

10. A burial vault comprising a base having an upper, substantially horizontal casket supporting surface, and downwardly extending side and end walls integral therewith and adapted to be supported adjacent the bottom of a grave and providing a lower, downwardly opening hollow space, a casket enclosing receptacle supported on said base, said receptacle comprising integral top, side and end walls and an open bottom, said bottom being closed by the top wall of said base, and a sheet metal inner casing supported on said casket supporting surface, said casing being pre-formed and comprising sheet metal top and side walls hermetically sealed along their meeting joints and having an open bottom, said open bottom being effective to permit the casing to be lowered upon said casket supporting surface to enclose a casket thereon, prior to the closing of the receptacle.

11. A vault construction comprising a base and a casket enclosing receptacle, said base comprising a supporting floor and side and end walls integral therewith and projecting downwardly therefrom, the upper outer margins of the base being provided with downwardly and outwardly inclined surfaces, said receptacle comprising a top wall and downwardly projecting side and end walls integral therewith, the lower edges of said downwardly projecting walls being provided with downwardly and outwardly inclined surfaces

mating with the surfaces on said base, whereby moisture may drain downwardly and outwardly through the joint between the inclined surfaces.

12. A vault construction comprising a substantially horizontal casket supporting floor, downwardly projecting supporting flanges extending around the margins of said floor and supported substantially at the bottom of a grave, a casket enclosing hood comprising a top wall and integral downwardly projecting side and end walls adapted to be supported along their lower edges around the margins of said floor, and moisture drainage means comprising a pipe positioned substantially centrally with respect to said floor and extending therethrough, said pipe having a goose-neck bend therein providing a liquid seal to prevent the passage of air and gas through said drainage means.

13. A vault construction comprising a unitary, cast concrete foundation slab adapted to be placed in the bottom of a grave, a substantially horizontal casket supporting floor spaced upwardly from said slab, downwardly projecting supporting flanges extending around the margins of said floor and supported at their lower ends on the margins of said slab, a casket enclosing hood comprising a top wall and integral downwardly projecting side and end walls adapted to be supported along their lower edges around the margins of said floor, and moisture drainage means comprising a pipe positioned substantially centrally with respect to said floor and extending therethrough and terminating adjacent the upper surface of said foundation slab, said pipe having a goose-neck bend therein providing a liquid seal to prevent the passage of air and gas through said drainage means.

14. A vault construction comprising, in combination, a foundation slab, a substantially horizontal casket supporting floor, and upwardly and downwardly projecting marginal flanges formed integrally with said floor, the downwardly projecting flanges being supported upon said slab and defining a hollow space below said floor, the upwardly projecting flanges defining a casket receiving chamber, a cover slab for said chamber, and a preformed inner casing comprising sheet metal top and side walls hermetically sealed along their meeting joints and having an open bottom, said open bottom being effective to permit the casing to be lowered upon said floor to enclose a casket supported thereon prior to the closing of said chamber.

15. A vault construction comprising, in combination, a foundation slab, a substantially horizontal casket supporting floor, and upwardly and downwardly projecting marginal flanges formed integrally with said floor, the downwardly projecting flanges being supported upon said slab and defining a hollow space below said floor, the upwardly projecting flanges defining a casket receiving chamber, a cover slab for said chamber, a preformed inner casing comprising sheet metal top and side walls hermetically sealed along their meeting joints and having an open bottom, said open bottom being effective to permit the casing to be lowered upon said floor to enclose a casket supported thereon prior to the closing of said chamber, and drainage means comprising a pipe extending through said floor from a point within said inner casing to a point adjacent said foundation slab.

ROBERT SIMPSON.
